UNITED STATES PATENT OFFICE.

EDWARD L. WATROUS, DECEASED, LATE OF EL PASO, TEXAS, BY AGNES B. WATROUS,
EXECUTRIX, OF EVANSTON, ILLINOIS.

APPARATUS FOR METAL-COATING WIRE, CHAIN, WOVEN-WIRE FENCING, AND THE
LIKE.

Application filed September 20, 1919. Serial No. 325,255.

To all whom it may concern:

Be it known that EDWARD L. WATROUS, deceased, late a citizen of the United States, formerly residing at El Paso, in the county 5 of El Paso and State of Texas, did invent certain new and useful Improvements in Apparatus for Metal-Coating Wire, Chain, Woven-Wire Fencing, and the like, of which the following is a specification.

10 This invention relates to a method and apparatus for plating such metallic articles as wire, chain, woven wire fencing and the like with non-corrosive metal such as zinc or the like.

15 In such metallic coating operations as galvanizing and the like, it is highly desirable to subject the articles, immediately after being dipped in the coating bath, to centrifugal action, in order to throw from 20 the article being coated any excess material that may be adhering thereto, in order to effect a finished product free from any undesirable excrescences or rough portions caused by the adhering thereto of solidified 25 excess coating material. In Patent No. 1, 221,397, issued April 3, 1917, is disclosed a method of metal plating, in which such small articles as bolts, screws, nuts, and the like are dipped in a spleter bath and then 30 subjected to centrifugal action by placing the containing basket in a centrifugal machine and rotating the same therein, together with its contents. However, such material as wire, chain, woven wire fencing 35 and the like from their very nature could not be handled in the apparatus and by the manner disclosed in said Patent No. 1,221, 397. It is the function of the present invention to make possible the successful 40 handling, coating and subjecting to centrifugal action such unwieldy materials as those last mentioned.

Among the objects of this invention are to make possible the successful handling 45 and coating of such unwieldy materials as wire, (including both plain wire and barbed wire), chain, woven wire fencing and the like by dipping the same in a heated metallic bath, and after removal from said bath 50 subjecting the material in question to centrifugal force, whereby to throw therefrom any excess coating material to result in a finished product free from any rough portions or

undesirable protuberances; further to provide special apparatus for effecting this result; further to provide means for sufficiently separating the overlapping strands when coating such materials as smooth wire or the like; further to provide a specially constructed reel, upon which to wind the material to be coated and also provide means to prevent any coating material that may have become chilled by contact with other parts being thrown from the interior upon the coated material; further to provide apparatus upon which the reel may be placed and rotated; and such further objects, advantages and capabilities as will later more fully appear.

This invention further resides in the combination, construction and arrangement of parts illustrated in the accompanying drawings, and while there is shown therein a preferred construction it is to be understood that the same is susceptible of modification and change without departing from the spirit of the invention.

In the drawings:

Figure 1 is a perspective view partly broken away showing a preferred form of reel for use in carrying out this invention.

Fig. 2 is a vertical transverse section through Figure 1, and showing the barrel of the reel as having barbed wire wrapped thereon.

Fig. 3 is a side elevation partly broken away, showing an apparatus upon which the reel may be placed to be rotated.

Fig. 4 is a plan view of the left hand portion of Fig. 3.

Fig. 5 is an end elevation of the reel shown in Fig. 1, but having a plurality of slotted plates added thereto to accommodate rods for separating the strands when coating smooth wire.

Fig. 6 is a vertical transverse section of the reel shown in Fig. 5, and showing several rounds of smooth wire wrapped thereon.

Fig. 7 is a modification of the machine shown in Fig. 3 and illustrating the spindle upon which the reel is to be placed as occupying a horizontal rather than a vertical position.

The present invention contemplates the provision of a suitable reel or the like upon

which such lengthy materials as wire, chain, woven wire fencing and the like may be wrapped, after which the reel with its contents will be immersed in a heated 5 spelter bath, or bath of other desirable material, the reel and its contents then removed from the bath and placed upon the rotatable spindle of a centrifugal machine, which spindle will then be rotated at a sufficient 10 speed to hurl by centrifugal force any excess coating material while yet soft from the article being coated. After the centrifugal machine has been stopped the wire or other similar material may be unwound 15 from the reel and rebundled for shipment if desired, or a cheap metal reel could be provided and sold with the wire or the like.

Referring to Fig. 1, there is provided a suitable reel comprising the spaced apart angle bars 1 positioned at each corner of the drum or barrel of the reel and spaced apart, preferably such a distance as to form a barrel of square cross-section. These bars 25 1 extend the full length of the drum or barrel and have secured thereto at their respective ends, as shown, the parallel spaced apart angle bars 2 and 3, which bars 2 and 3 have in turn secured to them at right angles thereto the parallel spaced apart bars 4 and 5 respectively, whereby to provide outwardly projecting arms at each end of the reel to confine the wound material on the drum or barrel of the reel. Secured 30 to the inside of each of the angle bars 1, and extending entirely around the drum or barrel of the reel is the metal sheathing 6, the function of which being to prevent any of the coating material which may have become chilled by coming in contact with the spindle, to be hereinafter described, from becoming thrown onto the work wound on the reel. The wire, chain, woven wire fencing or the like to be coated may, if desired, be wound on the reel constructed as 35 above described. However, for the purpose of preventing formation of short kinks in such wire or the like, and also prevent the same from lying too flat against the barrel 40 of the reel there is provided, extending longitudinally of the central portion of each face of the drum or barrel and separated therefrom by the cross bars 4 and 5, the angle bars 7 which are positioned with one 45 flange extending radially outward. The effect of these bars 7 is to give the drum or barrel a substantially octagonal cross-section, thus relieving the wire from any short 50 kinks, and which wire, chain, or the like when wrapped upon the reel will assume the position illustrated in Fig. 2. It will be noted that the drum or barrel of the reel just described is of hollow open ended formation, whereby after being withdrawn 55 from the spelter or other coating material

it may be quickly slipped over the spindle 8 of the centrifugal machine now to be described.

The centrifugal machine used for subjecting the reel and its contents to centrifugal action comprises the shaft 9, mounted by means of the step bearing 10 and the upper bearing 11 for rotation therein and geared by means of suitable bevel gears to the shaft 12, which shaft is in turn rotated by means of a belt or the like associated with the drive wheel 13. By rotating the wheel 13, the spindle 8 will be caused to rotate in an obvious manner. The spindle 8, as shown in Figures 3 and 4, is made up of the spaced apart angle bars 14, so arranged as to snugly receive the hollow drum or barrel of the reel. The bars 14 near their upper ends are made to converge whereby to facilitate the easy and quick 85 positioning of the reel thereon, and are secured by means of bolts or the like at their bottom ends to the supporting table 15, which rotates with the shaft 9, and are suitably secured together at their upper ends 90 by the rectangular band 16. It is obvious that any suitable form of clutch mechanism for throwing the centrifugal machine into and out of operation, and also a suitable 95 brake band for quickly stopping the same after performing its function, may be incorporated therein as desired, illustrations of such clutch and brake band being found in Fig. 7.

The reel as described above is best adapted for the reception of such materials as barbed wire, chain, woven wire fencing, or other materials of such nature that when wound upon themselves their component parts will not lie too closely together, whereby to prevent the ready access of the coating material between the various parts when the reel and its contents are dipped in the spelter bath or the like as in galvanizing. In order to adapt this reel to having wound thereon such material as smooth wire which, due to its smoothness, would permit adjacent strands to lie so closely together as to prevent the ready access of the coating material to all parts of the wire, the reel is shown in Figures 5 and 6 as provided at each end with a plurality of circumferentially spaced slotted plates 20, secured by means of bolts, rivets or the like to the bars 2, 3, 4 and 5, and preferably extending at right angles in each of the corner angles formed by the intersection of the adjacent ones of said bars. The slots 21 in the plates 20 are preferably open at their outer ends, however, it is obvious that any other form of mechanical equivalent may be used in place of such plates. The plates 20 are so arranged upon the opposite ends of the reel that they fall in pairs with their slots in alignment, whereby a rod 22 of sufficient 130

length may be readily inserted in each of the said aligned slots. In using this form of reel one or two layers of smooth wire are wrapped upon the drum or barrel of the reel as shown in Fig. 6, after which one of the rods 22 is inserted in each pair of aligned slots 21 and moved to the bottom thereof. The wrapping of the wire upon the barrel is then proceeded with until one or two more layers have been added, these latter layers falling on the outside of the first inserted rods 22, after which another series of rods 22 is inserted in the slots 21 in a similar manner, and the winding again proceeded with and one or two further layers wound around the exterior of the last positioned rods 22. This is continued until the desired amount of wire is wrapped upon the reel, after which the end of the wire is suitably secured in any desired manner and the reel with its contents dipped in the spelter bath, or other suitable coating material. As a result of inserting the rods 22 in the slots 21 during the wrapping of the wire upon the reel there will be formed between every other one or two layers of wire the spaces or interstices 23, which provide for the ready access of the coating material between the various strands or layers of wire which otherwise, due to their smoothness, would lie so close together as to prevent this access of coating material. After removal from the spelter bath, or the like the reel and its contents are positioned as described above upon the spindle 8 of the centrifugal machine, which is then caused to rotate at sufficient speed to throw off any excess coating material which may be upon the contents of the reel.

When coating such wide materials as woven wire fencing and the like the weight of the reel and its contents may be such as to render it inconvenient to lift the same to sufficient height to cause it to slip into position over the spindle 8. In order to obviate this difficulty there is shown in Fig. 7 a centrifugal machine so arranged that the spindle 8' thereof will fall in a horizontal instead of a vertical position. By the use of this form of machine the reel and its contents, when the same should possess considerable weight, may be readily and quickly slid upon the spindle 8', locked in position by any suitable form of locking means and then rotated as described above. As shown in Fig. 7, there is provided a suitable sliding friction clutch 25 operated by the handle 26 to contact with the driving wheel 13', and also a suitable brake band 27, by means of which friction may be caused between the same and the brake wheel 28, whereby to quickly bring the machine to a stop after the power has been thrown off. It will also be understood that there will be provided a suitable hood 30 around the

rotating reel whereby to prevent the undesirable flying of the particles of coating material being thrown off from the contents of the reel in all directions.

Having now described the invention,

70

What is claimed is:

1. In galvanizing apparatus, a reel adapted to be placed on a rotatable spindle and comprising a barrel having a sheet metal body and longitudinally extending angle bars at the corners of the barrel, and outstanding arms at each end whereby to confine on the barrel such material as wire, chain, woven wire fencing and the like to be coated.

75

2. In galvanizing apparatus, in combination a spindle, a reel adapted to have wound thereon wire, chain, woven-wire fencing or other material to be coated, said reel being hollow and of a configuration to readily slip on said spindle, and means to rotate said spindle, reel and contents to throw any excess coating material from the contents of the reel, said reel having on its drum or barrel a sheathing to prevent any spelter that may have become chilled by the spindle or other adjacent parts from becoming thrown on the contents of the reel.

80

3. In galvanizing apparatus, a reel adapted to have wound thereon wire, chain, woven-wire fencing or the like to be coated, said reel comprising a hollow open-ended barrel, a plurality of spaced angle bars fastened to the barrel longitudinally thereof, and a plurality of transversely projecting bars at each end of said barrel.

85

4. In galvanizing apparatus, a reel adapted to have wound thereon wire, chain, woven-wire fencing or the like to be coated, said reel comprising a hollow open-ended barrel formed of a plurality of spaced bars, a plurality of transversely projecting bars at each end of said barrel, and a sheathing around the interior of said barrel for the purpose set forth.

90

5. In galvanizing apparatus, a reel comprising a plurality of longitudinally extending bars spaced to form an open work barrel, a pair of parallel spaced bars secured upon each end of the outside of said barrel, a pair of parallel spaced bars secured to each of said first mentioned pairs of bars respectively and at right angles thereto, the ends of each of said pairs of bars projecting transversely beyond said barrel.

110

6. In galvanizing apparatus a reel comprising a plurality of longitudinally extending angle bars spaced to form an open work barrel, a pair of parallel spaced bars secured upon each end of the outside of said barrel, a pair of parallel spaced bars secured to each of said first mentioned pairs of bars respectively and at right angles thereto, the ends of each of said pairs of bars projecting transversely beyond said

115

120

125

120

barrel, and a sheathing secured to said barrel for the purpose set forth.

7. In galvanizing apparatus, a reel adapted to have wound thereon wire, chain, woven-wire fencing or similar material to be galvanized, and comprising a drum or barrel portion, projecting arms at each end of said barrel, and means between said projecting arms to hold cross-rods for the purpose set forth.

8. In galvanizing apparatus, a reel adapted to have wound thereon wire, chain, woven-wire fencing or similar material to be galvanized, and comprising a drum or barrel portion, projecting arms at each end of said barrel, and means between said projecting arms to hold cross-rods for the purpose set forth, said means comprising slotted plates suitably spaced around said barrel at each end thereof.

9. In galvanizing apparatus, a reel adapted to have wound thereon wire, chain, woven-wire fencing or similar material to be galvanized, and comprising a barrel formed of a longitudinally extending angle iron at each corner, a pair of spaced parallel bars secured to said angle irons at each end of said barrel, a second pair of parallel spaced bars secured to each of said first pairs and at right angles thereto, and a longitudinally extending angle iron secured to said bars on each of the four sides of said barrel with their flanges extending outwardly whereby to form raised projections on which to wind the contents of the reel.

10. In metal coating apparatus, a reel adapted to have wound thereon lengthy material to be coated, and comprising a hollow open-ended barrel adapted to be removably positioned on a rotatable spindle, projecting arms at each end of said barrel to confine thereon the wound material, and a longitudinally extending outwardly projecting flange on each of the four sides of said barrel whereby to cause said material to substantially follow the contour of an octagon in winding.

11. In metal coating apparatus, in combination, a rotatable spindle, a reel adapted to have wound thereon lengthy materials to be coated such as wire, chain, woven-wire fencing and the like, said spindle being arranged horizontally whereby reels having wound thereon such wide materials as woven-wire fencing and the like may after being dipped in a coating bath be readily positioned on said spindle without lifting to great heights, and means for rotating said spindle and reel to throw any excess coating material from the material wound on the reel, a sheathing around the reel to catch the material cast off.

12. In metal coating apparatus, a reel comprising a drum or barrel upon which may be wound wire to be coated, means to

prevent the first layers of wire from lying too close to the parts of said drum or barrel, projecting arms at the ends of said drum or barrel, and radially extending slotted plates circumferentially spaced upon each end of said drum or barrel, said plates being arranged at opposite ends of the drum or barrel in opposed pairs with the slots of each pair in alinement whereby in winding wire on said reel a rod may be placed in each pair of alined slots to raise one or more layers of wire from the subjacent layer or layers whereby to permit the ready access of the coating material between the strands of wire when the reel and contents are being dipped.

13. In galvanizing apparatus, a reel adapted to be placed on a rotatable spindle and comprising a barrel having walls of sheet material and longitudinally extending bars at the corners of the barrel, and spaced outwardly extending arms at each end of the barrel to confine material wound on the barrel.

14. A reel adapted to be placed upon a rotating spindle and comprising a barrel having walls of sheet material and longitudinally extending bars at the corners of the barrel, spaced parallel outstanding arms fastened to the ends of said bars to confine material wound upon the barrel to be coated.

15. A reel adapted to be placed upon a rotating spindle and comprising a barrel having walls of sheet material and longitudinally extending bars at the corners of the barrel, pairs of outstanding cross arms fastened to the ends of said bars and adapted to confine material wound on the barrel.

16. A reel adapted to be placed upon a rotatable spindle and comprising a barrel, longitudinally extending bars at the corners of the barrel, spaced parallel cross arms fastened to the ends of said bars and adapted to include therebetween material to be wound on the barrels and to be coated thereon.

17. In coating apparatus, a reel adapted to have material to be coated wound thereon, said reel comprising a hollow open ended barrel having a sheet metal body and a plurality of spaced bars fastened to the body longitudinally thereof, a plurality of transversely projecting bars at each end of said longitudinal bars, and means to cause a rapid rotation of the reel for casting off excess coating material therefrom.

In witness whereof, I hereunto subscribe my name to this specification in the presence of one witness.

AGNES B. WATROUS,
Executrix of the will of Edward L. Watrous, deceased.

Witness:

MERRILL M. BLACKBURN,

Certificate of Correction.

It is hereby certified that in Letters Patent No. 1,462,589, granted July 24, 1923, upon the application of Agnes B. Watrous, of Evanston, Illinois, executrix of Edward L. Watrous, deceased, for an improvement in "Apparatus for Metal-Coating Wire, Chain, Woven-Wire Fencing, and the Like," errors appear in the printed specification requiring correction as follows: Page 1, line 29, for the misspelled word "spleter" read *spelter*, and line 86, for the word "party" read *partly*; page 2, lines 96-97, for the misspelled word "incorporated" read *incorporated*; page 3, line 123, claim 6, strike out the word "angle"; page 4, line 104, claim 16, after the word "extending" insert the word *angle*; and that the said Letters Patent should be read with these corrections therein that the same may conform to the record of the case in the Patent Office.

Signed and sealed this 9th day of October, A. D., 1923.

[SEAL.]

WM. A. KINNAN,
Acting Commissioner of Patents.
